(57) CLAIM

The ornamental design for the shaving razor cleaning device, as shown and described.

DESCRIPTION

FIG. 1 is a perspective view of the present invention; and FIG. 2 is a front plan view of the present invention; and FIG. 3 is a rear plan view of the present invention; and FIG. 4 is a left side view of the present invention; and FIG. 5 is a right side view of the present invention; and, FIG. 6 is a top view of the present invention. Wherein the broken lines herein illustrate environment only and do not form a portion of the claimed invention.

1 Claim, 4 Drawing Sheets

FIG. 2

FIG. 3

FIG. 4

FIG. 5

FIG. 6
